Primary Examiner — Rachel A. Voorhies*Assistant Examiner* — Benjamin D. Wannemacher(74) *Attorney, Agent, or Firm* — CKC & Partners Co., LLC(57) **CLAIM**

The ornamental design for a cord stopper as shown and described.

DESCRIPTION

FIG. 1 is a perspective view of a cord stopper showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken from FIG. 1 along line 8-8; and,

FIG. 9 is a schematic view of two cords passing through the cord stopper of my new design, wherein the dashed lines are included for the purpose of illustrating environmental structures and form no part of the claimed design.

1 Claim, 6 Drawing Sheets(56)
